UNITED STATES PATENT OFFICE

JONAS A. ROSENFIELD, OF DALLAS, TEXAS

DESIGN FOR A COMBINED LUNCH AND SOFT-DRINK STAND

Application filed May 19, 1928. Serial No. 26,765. Term of patent 14 years.

To all whom it may concern:

Be it known that I, JONAS A. ROSENFIELD, a citizen of the United States, residing at Dallas, in the county of Dallas and State of Texas, have invented a new, original, and ornamental Design for Combined Lunch and Soft-Drink Stand, of which the following is a specification, reference being had to the accompanying drawings, forming part thereof.

I claim:

The ornamental design for a combined lunch and soft drink stand, as shown.

In testimony whereof I have signed my name to this specification.

JONAS A. ROSENFIELD.
